L. E. SHIPMAN,
LOOSE LEAF BINDER,
FILED JUNE 18, 1921

Inventor:
Gester E. Shipman,
by his attorney,
Charles R. Searle,

UNITED STATES PATENT OFFICE.

LESTER E. SHIPMAN, OF NEW YORK, N. Y.

LOOSE-LEAF BINDER.

Application filed June 18, 1921. Serial No. 478,676.

To all whom it may concern:

Be it known that I, LESTER E. SHIPMAN, a citizen of the United States, residing in the city of New York, borough of Queens, 5 in the county of Queens and State of New York, have invented a certain new and useful Improvement in Loose-Leaf Binders, of which the following is a specification.

The invention relates to binders in which 10 the mass of superposed loose leaves is held by flexible media extending through marginal perforations or notches in the leaves, and the object of the invention is to provide easily operated means for confining the 15 leaves reliably; which shall afford an exceptionally wide range in the thickness of the mass accommodated; permit leaves to be easily and quickly inserted or removed, and which shall be simple in construction and 20 eminently durable.

The invention consists in certain novel features and details of construction and arrangement by which the above objects are attained, to be hereinafter described and 25 claimed.

The accompanying drawings form a part of this specification and show an approved form of the invention.

Figure 1 is a face view of the binder 30 with the front cover turned to expose the bound leaves.

The remaining figures are on a larger scale.

Figure 2 is a transverse section through 35 the back of the binder with the covers closed. The plane of section is indicated by the line II in Figure 1.

Figure 3 is a corresponding section taken on the line III in Figure 1, and with a filling 40 piece in position for service.

Figure 4 is a longitudinal section through one end of the binding strips and their connections, with the filling piece and leaves omitted.

Figure 5 is a plan view of one end portion of one of the binding strips.

Similar reference numerals indicate the same parts in all the figures.

Referring to the drawings, 1 is the front 50 cover and 2 the back cover, joined by the flexible back 3 of sufficient width to permit the covers to be widely separated as required in accommodating the varying mass of leaves 4 to be inclosed. The leaves are shown 55 as perforated on the back margin, as at 5,

but they may be notched in the usual manner if preferred.

Attached to each cover is a binding strip shown as, but not necessarily, composed of two portions, one, marked 7, adapted to lie upon the leaves and having the flexible hinge connection 6 to the cover, and the other portion, marked 9, lying on the outer face thereof and secured thereto by the hollow rivets 10 or otherwise. The margins of both portions are notched as at 8 and 11.

The flexible means employed for binding the leaves and binding strips together are shown as chains 12, one for each end of the binding strips, passed loosely through the 65 perforations 5 in the leaves and through the notches 8 and 11, and on each end of each portion 9 of the binding strips is a lever 13 pivoted thereto at 14 and adapted to swing thereon. Each lever has a nose 15 shaped to 70 engage a link of the chain presented in the notch 11, by co-action with the edges of the notch, and hold the chain reliably when the lever is swung into position with its edges parallel with the edges of the binding strip. 75 A boss 16 on the portion 9 engages a recess at 17 on the lever when thus positioned and holds the lever yieldingly in the locked condition. The raised end 18 serves as a handle for swinging the lever to lock or free the 80 chain.

Each end of each chain 12 is equipped with a needle 19 to aid in threading it through the perforations in the leaves.

In the operation of binding the leaves, the 85 chains 12 are first locked at any convenient link to the lower binding strip by setting the levers 13, and the free ends of the chains 90 disengaged from the upper binding strip. The leaves are then threaded on the chains 95 and the latter inserted in the notches of the upper binding strip which is pressed firmly down on the mass of leaves while the chains are successively drawn taut and locked by 100 swinging the upper levers 13 each into engagement with the link presented at the notch. The loose ends of the chains are folded upon the upper face of the binding strip and may be held by slides 20 mounted on such strip.

In case the thickness of the mass of leaves 105 should be too great to permit the proper presentation of a link to the lever, and too small to be properly compressed by engaging the succeeding link, especially when 110

notched leaves are used, a filling strip or piece is introduced between the upper binding strip and the uppermost leaf to increase the thickness and thus take up any slack in the chain. As shown in the drawings, see Figures 2 and 3, the filling piece consists of a strip 21 loosely hinged at 22 to the front cover 1 and is notched as at 23 to accommodate the chains. When not in use the filling piece lies idly between the inner edge of the mass of leaves 4 and the back 3 as in Figure 2, and when introduced lies beneath the upper binding strip, as in Figure 3, and supplies the required increase in thickness.

15 The device permits the use of long chains with both ends detachably secured to the binding strips thus affording great latitude in capacity and permitting the addition of leaves to be made from front or back, or if 20 notched leaves are used they may be inserted or removed from any portion of the mass by simply slackening the chains.

The chains and their locking means are unaffected by atmospheric or climatic conditions and afford a strong, durable binding medium not liable to fracture or derangement and offer a simple and highly efficient means of great range for securely holding a small or large mass of leaves or like matter 25 with all the advantages offered by more complicated devices. The adjusting means are entirely exposed and accessible.

Modifications may be made in the forms and proportions within wide limits without departing from the principle of the invention. Other types of chains may be substituted for the referred form shown, and the locking means for engaging the chains may be widely varied as found necessary or desirable in adapting the invention to various 30 conditions of service or price.

I claim:

1. In a device of the character set forth, binding strips adapted to receive between them the leaves to be bound and having marginal notches, chains each extended loosely through such leaves and binding strips, and

means on both of said binding strips for detachably engaging links of said chains engaged in said notches. 50

2. In a device of the character set forth, a front cover and a back cover joined by a flexible back, a binding strip hinged to said front cover, a binding strip hinged to said back cover, said strips having marginal notches, chains extending loosely through said strips and lying in such notches, and levers mounted on said strips adjacent such notches, each adapted to engage detachably a link of the chain presented in its adjacent notch. 55

3. In a device of the character set forth, a front cover and a back cover joined by a flexible back, a binding strip hinged to said front cover, a binding strip hinged to said back cover, chains secured to one of said strips and extended loosely through the leaves to be bound and through the other of said strips, movable means mounted on the latter for detachably gripping said chains, and a filling piece hinged to one of said 65 covers and lying between said leaves and back, adapted to be inserted between said leaves and one of said binding strips. 70

4. In a device of the character set forth, binding strips having marginal notches, chains extending loosely through such notches, and levers pivotally mounted on said binding strips adjacent such notches, each adapted to co-act with the edges of its notch and engage detachably a link of its 75 chain. 80

5. In a device of the character set forth, binding strips having marginal notches, chains extending loosely through such notches, levers pivotally mounted on said binding strips adjacent such notches, each adapted to co-act with the edges of its notch and engage detachably a link of its chain, and means for holding said levers yieldingly 85 in the engaged position. 90

In testimony that I claim the invention above set forth I affix my signature.

LESTER E. SHIPMAN.
